WILLIAM O. WHEELER, OF DEPOSIT, NEW YORK.

Letters Patent No. 79,169, dated June 28, 1868.

IMPROVEMENT IN STREET-LAMPS.

The Schedule referred to in these Letters Patent and making part of the same.

TO ALL WHOM IT MAY CONCERN:

Be it known that I, WILLIAM O. WHEELER, of Deposit, in the county of Delaware, and State of New York, have invented new and useful Improvements in Street-Lamps; and I do hereby declare that the following is a full and exact description of the same, reference being had to the accompanying drawings, and to the letters of reference marked thereon.

This invention consists in certain devices, to be hereinafter more fully described, which are applied to a street-lantern and its enclosed tube, in order to facilitate the lighting and extinguishing of the gas.

It is well known that the lighting of street-lamps, as they are now constructed, is always attended with no inconsiderable difficulty, and greatly increased in stormy weather, when lamps are most needed, and that they require the services of many men to light and extinguish any large number of lamps.

The attendant must carry a ladder or steps, mount to the lamp, and open the door before the gas can be lighted, and often in stormy weather the gas is blown out before the door can be closed. It is obvious that to go through this tedious process at every lamp, to carry the ladder, fix it in place, mount, light the lamp, descend, and take up the ladder, must consume much time, and as the lamps must be all lighted nearly at the same time, a large force of men must be employed for the purpose. And nearly the same process must be repeated, turning off the gas in the morning.

My invention obviates the necessity of a ladder or mounting to the lantern, and requires only that the attendant carry a torch on a pole, of sufficient height to reach the vent from which the gas issues.

In order that those skilled in the art to which my invention appertains may be able to make the same and apply it to use, I will proceed to point out and illustrate more specifically its construction and operation.

In the annexed drawings, which make part of this specification—

Figure 1 is a view of one side of my street-lantern.

Figure 2 is a view of the valves on the bottom of the lamp, and the opening which they cover.

Figure 3 is a sectional view of the tube and its connection.

The same letters refer to identical parts in all the drawings.

The lantern is mainly of the ordinary construction, but is provided on the bottom with an opening, D, of sufficient size to admit a torch, the light of which is to ignite the gas. This opening may be covered by one of two valves, B and C, of shape corresponding to the opening, and pivoted so as to move horizontally over or from the opening. The valve B is simply pivoted upon the neck of the tube a, and moves closely down over the opening, entirely covering it. Both valves are provided with lugs, projecting downward in such position that they may be touched from beneath, and the valves thereby operated.

The tube a need not differ materially from the ordinary burner, except in this respect: The upper part, which may be made, for convenience, like the ordinary burner, slightly tapering, is not perforated longitudinally throughout, but has a diaphragm, m, across the passage, obstructing entirely the direct flow of the gas. Immediately above and below the diaphragm are two little orifices, f and g, opening outward. Over this tube a, and on its tapering part, is placed the sleeve b, constructed to fit accurately upon the tube, and rest upon a shoulder. On the inner surface of this sleeve, and arranged longitudinally, is a groove, e, of sufficient depth to allow the passage of the gas, and long enough to cover both the openings f and g.

To the lower part of the sleeve is attached firmly one of the valves, C, the tube serving as the pivot on which the whole turns simultaneously. The valves and sleeve are so arranged vertically that when the valves are pressed down closely over the opening, the groove in the inner surface of the sleeve shall be able exactly to cover both the openings f and g; and still further, the horizontal arrangement is such, that when the valve C is turned over the opening D in the bottom of the lantern, the slot or groove shall be turned aside from the openings, and thus these openings be covered closely. Above the sleeve is screwed a burner, with, if necessary, an intervening washer, or the tube may be prolonged with a burner, and simply a washer, or equivalent, be placed over the sleeve, to keep it in place.

The operation of my device is as follows: Let the valve C be turned over the opening D, when the sleeve, being turned with the valve, will move the slot or groove *e* away from the orifices *f* and *g*, and thus the gas is cut off. The attendant whose business it is to light the lamps carries a torch of sufficient length to enable him to reach the lamp, and by pressing the end of the torch against the lug *l* turns the valve C to the right, the arrangement being such that when the lug touches its limit on the right, the slot is brought over the openings *f* and *g*. A communication is thus established throughout the tube, and the free flow of gas permitted by way of the orifices and groove, and by passing the torch through the opening, the gas is easily lighted.

As the opening, D, made to admit the torch, is larger than is needed for supplying air, (the ordinary holes being made for that purpose,) and as the return of the valve C would cut off the gas; the valve B is provided, which may be turned from left to right, and thus close the lantern for the night: In the morning, when the lamp is to be extinguished, the attendant has only to place the torch-staff, or equivalent rod, against the lug *l*, and push back both valves from right to left, by the same movement cutting off the gas and closing the lantern for the day.

It is obvious that the details may be varied, or that devices may be provided for locking the valves without departing from the spirit of my invention.

It is also evident that the lighting of the lamps must be but the work of a moment, and in stormy, windy weather, the operation is effected much more certainly and easily.

Having thus-described my invention, what I claim, and desire to secure by Letters Patent of the United States, is—

1. A tube of a street-lamp, of the described construction, when provided with a diaphragm and opening and having communication effected or cut off by means of an enclosing sleeve, all as described, and for the purpose set forth.

2. In combination with the above devices I claim the valves, constructed and operated as described, and for the purpose set forth.

3. I claim a street-lamp, so constructed that the gas may be turned on or off by moving the valve which closes the orifices of the lamp, substantially for the purpose set forth.

This specification signed and witnessed, this 15th day of May, 1868.

WILLIAM O. WHEELER.
